[57]

ABSTRACT

[(2-Nitro-1-alkenyl)aryl]alkanoic (and alkenoic)acids and salts, esters and amide derivatives thereof, wherein the aryl ring may be further substituted by halogen, lower alkyl or hydrocarbylene substituents. The products are diuretic and saluretic agents and are prepared by treating an [(N-substituted formimidoyl)aryl]alkanoic (or alkenoic)-acid or ester with a nitroalkane or substituted nitroalkane. When the ester of the [(2-nitro-1-alkenyl)aryl]alkanoic (or alkenoic)-acid is obtained, it may be hydrolyzed to the desired [(2-nitro-1-alkenyl)aryl]alkanoic (or alkenoic)acid by conventional means.

5 Claims, No Drawings

[(2-NITRO-1-ALKENYL)ARYL]ALKANOIC (AND ALKENOIC)-ACIDS AND RELATED COMPOUNDS

This invention relates to a new class of chemical compounds which can be described generally as [(2-nitro-1-alkenyl)aryl]alkanoic (and alkenoic) acids and to the nontoxic, pharmacologically acceptable salts, esters and amide derivatives thereof. It is also an object of this invention to describe a novel method of preparation for the [(2-nitro-1-alkenyl)aryl]alkanoic (and alkenoic) acid products and their corresponding salts, esters and amides.

Pharmacological studies show that the instant products are effective diuretic and saluretic agents which can be used in the treatment of conditions associated with electrolyte and fluid retention and hypertension. When administered in therapeutic dosages, in conventional vehicles, the instant products effectively reduce the amount of sodium and chloride ions in the body tissues, lower dangerous excesses of fluid levels to acceptable limits and, in general, alleviate conditions usually associated with edema.

The [(2-nitro-1-alkenyl)aryl]alkanoic (and alkenoic)-acids (I, infra) of this invention are compounds having the following structural formula:

wherein R is alkyl, for example, lower alkyl such as methyl, ethyl, n-propyl, n-butyl, pentyl, hexyl and the like, alkoxy alkyl, for example, lower alkoxy lower alkyl such as methoxymethyl and the like, haloalkyl, for example, halo lower alkyl such as chloromethyl, bromomethyl and the like, trihalo lower alkyl, for example, trihalomethyl such as trifluoromethyl and the like, hydroxyalkyl, for example, hydroxy lower alkyl such as hydroxymethyl and the like, cyano, aralkyl, for example, mononuclear aralkyl such as benzyl and the like or cycloalkyl, for example, lower cycloalkyl such as cyclobutyl and the like; X is hydrogen, halo, for example, chloro, bromo, fluoro and the like or lower alkyl such as methyl and the like or, taken together, two X

radicals on adjacent carbon atoms of the benzene ring may be joined to form a hydrocarbylene chain (i.e., a divalent organic radical composed solely of carbon and hydrogen) containing 4 carbon atoms between their points of attachment, for example, 1,3-butadienylene and the like; Y is lower alkylene such as methylene, ethylene and the like or lower alkenylene, for example, vinylene, methyl substituted vinylene and the like; and n is an integer having a value of 1-4 and the non-toxic pharmaceutically acceptable salts thereof, for example, salts derived from the alkali metals and alkaline earth

metals, for example, the alkali metal and alkaline earth metal carbonates, hydroxides and lower alkoxides such as sodium carbonate, sodium hydroxide, magnesium carbonate, calcium hydroxide, potassium hydroxide, sodium methoxide and the like or from organic basis, for example, amines such as monoalkylamines, dialkylamines, tertiary amines or heterocyclic amines such as methylamine, dimethylamine, diethylamine, triethylamine, piperidine, pyrrolidine, morpholine and the like.

A preferred embodiment of this invention relates to the 4-[(2-nitro-1-alkenyl)aryl]acetic acids (Ia, infra) having the following structural formula:

wherein R¹ is alkyl, for example, lower alkyl such as methyl, ethyl and the like; X¹ and X² are hydrogen, lower alkyl such as methyl and the like or halo such as chloro and the like or X¹ and X², taken together, may be joined to form a 1,3-butadienylene linkage; and the non-toxic, pharmaceutically acceptable salts thereof as, for example, the alkali metal and alkaline earth metal salts such as the sodium salt, potassium salt and the like. The foregoing class of compounds exhibits particularly good diuretic and saluretic activity and represents a preferred subgroup of compounds within the scope of this invention.

The [(2-nitro-1-alkenyl)aryl]alkanoic (and alkenoic)-acids (I, supra) are conveniently prepared by treating an [(N-substituted formimidoyl)aryl]alkanoic (or alkenoic)acid or its corresponding ester derivative (II, infra) with a nitroalkane or substituted nitroalkane. Although the reaction may be conducted in the absence of a solvent, generally a solvent is employed. Suitable solvents include the lower alkanic acids such as acetic acid, propionic acid and the like. The reaction may be conducted at a temperature in the range of from about 20° to about 120°C.; however, in practice the reaction is conveniently conducted at the reflux temperature of the particular solvent employed. The following equation illustrates this reaction:

wherein R, X, Y and n are as defined above and R² is alkyl, for example, lower alkyl such as n-butyl, pentyl, hexyl and the like or cycloalkyl, for example, lower cycloalkyl such as cyclopentyl, cyclohexyl and the like and R³ is hydrogen or lower alkyl such as methyl, ethyl and the like. When an ester starting material is employed, that is, when R³ in formula II, supra, is lower alkyl, the resulting ester product (Ib) may be hydrolyzed to the corresponding acid by conventional means as, for example, by treatment with an aqueous mixture of hydrochloric acid and acetic acid.

The [(N-substituted formimidoyl)aryl]alkanoic (or alkenoic) acids and esters (II, supra) employed in the preparation of the [(2-nitro-1-alkenyl)aryl]alkanoic

treatment of the intermediate aldimine (IV, infra) thus obtained with water. The following equation illustrates this process:

(and alkenoic) acids and esters (Ib, supra) are conveniently prepared by treating a (formylaryl)alkanoic (or alkenoic)-acid or ester (III, infra) with a primary amine, for example, with an alkylamine such as a lower alkylamine as illustrated by n-butylamine, pentylamine, hexylamine and the like or a cycloalkylamine, for example, a lower cycloalkylamine such as cyclopentylamine, cyclohexylamine and the like. Although the reaction may be conducted without a solvent, any solvent which is inert or substantially inert to the reactants may be employed. To insure completion of the reaction, water immiscible solvents, which form an azeotrope with water, are generally employed; and benzene has proved to be particularly advantageous. The reaction is conveniently conducted at the reflux temperature of the particular solvent employed. The following equation illustrates this reaction:

wherein R², R³, X, Y and n are as defined above.

The (formylaryl)alkanoic (or alkenoic) acids and esters (III, supra) employed in the preparation of the [(N-substituted formimidoyl)aryl]alkanoic (and alkenoic) acids (II, supra) are either known compounds or may be conveniently prepared by treating a (cyanoaryl)alkanoic acid or ester (V, infra) with a reducing agent such as Raney nickel alloy in the presence of a suitable solvent such as formic acid followed by the

60 to afford the corresponding (formylaryl)alkanoic acid (IIIa, infra) which may be employed as such as a reactant or may be reduced with an appropriate reducing agent as, for example, with a metal catalyst on a suitable carrier such as 5-10 percent of a noble metal on carbon such as 5 percent rhodium on carbon and the like, to yield the corresponding (formylaryl)alkanoic acid (IIIb, infra). The following equation illustrates this process:

wherein X' is hydrogen or halogen or two X' radicals, on adjacent carbon atoms of the benzene ring, may be joined to form a hydrocarbylene chain; Y' is lower alkenylene such as vinylene, methyl substituted vinylene and the like and Y'' is lower alkylene such as ethylene, methyl substituted ethylene and the like.

The (cyanoaryl)alkanoic (or alkenoic)acids (V, supra) employed in the preparation of the (formylaryl)alkanoic (or alkenoic)acids and esters (III, supra) are conveniently prepared by either of two alternate methods. One method comprises treating a nuclear substituted (aminoaryl)alkanoic (or alkenoic)acid (VI, infra) with a solution of sodium nitrite and a strong acid such as hydrochloric acid, sulfuric acid, fluoboric acid and the like to form the corresponding diazonium salt followed by treating said diazonium salt with an aqueous solution of cuprous cyanide, potassium cyanide and sodium acetate. The following equation illustrates this process:

A second method for preparing the (cyanoaryl)alkanoic (or alkenoic)acids and esters (Vb) and one which is limited to the (cyanoaryl)alkanoic (or alkenoic)acids and esters wherein X'' in formula Vb is hydrogen or lower alkyl or two X'' radicals, on adjacent carbon atoms of the benzene ring may be joined to form a hydrocarbylene chain, comprises treating a nuclear halo substituted arylalkanoic (or alkenoic)acid or ester (VII, infra) with cuprous cyanide in the presence of a suitable aprotic solvent such as dimethylformamide and the like and an organic base such as pyridine and the like. The reaction is conveniently conducted at a temperature in the range of from about 100°C. to about 150°C.; however, in practice, the reaction is generally conducted at the reflux temperature of the solvent system employed. The following equation illustrates this process:

VII

wherein R^3 , Y and n are as defined above; X'' is hydrogen or lower alkyl or two X'' radicals, on adjacent carbon atoms, may be joined to form a hydrocarbylene chain and X^4 is halo such as bromo and the like.

The nuclear amino substituted arylacetic acids (VIa, infra) employed as starting materials in the preparation of the (cyanoaryl)alkanoic (and alkenoic) acid derivatives (V, supra) are conveniently prepared by the hydrolysis of an (acetamidophenyl)thioacetomorpholide (VIII, infra) with an aqueous solution of an inorganic acid such as hydrochloric acid and the like. The following equation illustrates this process:

wherein X and n are as defined above.

The (acetamidophenyl)thioacetomorpholides (VIII, supra) employed in the preparation of the nuclear amino substituted phenylacetic acids (VIa, supra) are prepared by treating an acetamidoacetophenone (IX, infra) with sulfur and morpholine at temperatures in the range of from about 100° to 130°C. for a period of from 1 to 10 hours. The following equation illustrates this process:

wherein X and n are as defined above.

The acetamidoacetophenones (IX, supra) employed in the preparation of the (acetamidophenyl)thioacetomorpholides (VIII, supra) are either known compounds or may be prepared by treating an appropriately substituted acetanilide (X, infra) with an acetyl halide such as acetyl chloride and the like in the presence of aluminum chloride. The reaction may be conducted without a solvent; however, in general, solvents which are inert or substantially inert are employed such as dichloromethane, benzene, nitrobenzene, carbon disulfide and the like. The following equation illustrates this reaction:

wherein X and n are as defined above.

Included within the scope of this invention are the non-toxic, pharmacological acceptable salts of the instant products. In general, any base which will form a salt with the foregoing [(2-nitro-1-alkenyl)aryl]alkanoic (and alkenoic)-acids and whose pharmacological properties will not cause an adverse physiological effect when ingested by the body system is considered as being within the scope of this invention. Suitable bases thus include, for example, those derived from the alkali metals and alkaline earth metals, for example, the alkali metal and alkaline earth metal carbonates, hydrox-

ides and alkoxides such as sodium carbonate, sodium hydroxide, magnesium carbonate, calcium hydroxide, potassium hydroxide, sodium ethoxide and the like, ammonia, primary, secondary and tertiary amines, for example, mono-lower alkylamines such as methylamine, ethylamine and the like, di-lower alkylamines such as dimethylamine, diethylamine and the like, tri-lower alkylamines such as triethylamine and the like, alicyclic amines such as cyclopentylamine and the like

or heterocyclic amines such as piperidine, pyrrolidine, morpholine and the like.

Also included within the scope of this invention are the ester and amide derivatives of the instant products which are prepared by conventional methods known to those skilled in the art. Thus, for example, if other ester derivatives besides those disclosed are desired, they may be prepared by the reaction of a [(2-nitro-1-alkenyl)aryl]-alkanoic (or alkenoic)acid of this invention with an alcohol as, for example, with a lower alcohol such as methanol, ethanol, n-propanol and the like. The amide derivatives of the [(2-nitro-1-alkenyl)aryl]alkanoic (and alkenoic) acids of this in-

vention may be prepared by converting a [(2-nitro-1-alkenyl)aryl]alkanoic (or alkenoic)acid to its corresponding acid chloride by treating said acid with thionyl chloride followed by treating the acid chloride formed with ammonia or an appropriate mono-lower alkylamine or di-lower alkylamine to produce the corresponding amide compound or by treating the esters heretofore described with ammonia or an amine. These and other equivalent methods for the preparation of the ester and amide derivatives of the instant products will be apparent to one having ordinary skill in the art and to the extent that said derivatives are both non-toxic and physiologically acceptable to the body system, said derivatives are the functional equivalent of the corresponding [(2-nitro-1-alkenyl)aryl]alkanoic (and alkenoic)acids.

The examples which follow illustrate the [(2-nitro-1-alkenyl)aryl]alkanoic (and alkenoic)acids of this invention and the method by which they are prepared. However, the examples are illustrative only and it will be apparent to those having ordinary skill in the art that all of the products embraced by formula I, supra, may also be prepared in an analogous manner by substituting the appropriate starting materials for those set forth in the examples.

EXAMPLE 1

[4-(2-Nitro-1-Propenyl)phenyl]acetic Acid

A mixture of ethyl (4-formylphenyl)acetate (3.8 g., 0.02 mole), benzene (30 ml.) and n-butylamine (1.46 g., 0.02 mole) is refluxed under a constant water separator until evolution of water is complete (about 2 hours). The benzene then is evaporated under reduced pressure to afford ethyl [4-(N-n-butylformimidoyl)phenyl]acetate. The pale yellow ethyl [4-(N-n-butylformimidoyl)phenyl]acetate is dissolved in acetic acid (20 ml.) and nitroethane (5.4 g., 0.07 mole) is added. The mixture is heated to boiling and then allowed to cool. The yellow-green solution then is poured into ice water (125 ml.). The green oil that separates is extracted with ether. The ether extract is washed with water, dried over sodium sulfate, filtered and the ether evaporated. The residual oil, crude ethyl [4-(2-nitro-1-propenyl)phenyl]-acetate, is dissolved in a mixture of acetic acid (30 ml.), water (20 ml.) and concentrated hydrochloric acid (1.0 ml.). The mixture is refluxed for 1 hour and then kept at 20°-25°C. for 2 days. The pale green crystals that separate are collected on a filter and crystallized from an ethanol-water solution (1:1) to obtain 1.6 g. of [4-(2-nitro-1-propenyl)-phenyl]acetic acid, m.p. 149°-152°C.

Elemental analysis for $C_{11}H_{11}NO_4$:

Calc.: C, 59.72; H, 5.02; N, 6.33;

Found: C, 59.70; H, 4.92; N, 6.48.

EXAMPLE 2

[3-Chloro-4-(2-Nitro-1-Propenyl)phenyl]acetic Acid

Step A: (3-Chloro-4-Acetamidophenyl)thioacetomorpholide

An intimate mixture of 3-chloro-4-acetamidoacetophenone (30 g., 0.143 mole), precipitated sulfur (4.6 g., 0.143 mole) and morpholine (13.5 g., 0.158 mole) is heated gradually until a melt forms (at about 100°C.). The mixture then is heated up to 120°-130°C. and kept at this temperature for 7 hours. The hot mixture then is poured into water (250 ml.) On gentle warming, the resulting syrup solidifies to a dark

yellow mass, which is pulverized in a mortar, collected on a filter and washed with water. After crystallization from 59 percent alcohol, there is obtained 31.3 g. (72 percent yield) of (3-chloro-4-acetamidophenyl)thioacetomorpholide, m.p. 125°-126.5°C.

Elemental analysis for $C_{14}H_{17}CLN_2O_2S$:

Calc.: C, 53.75; H, 5.48; S, 10.25;

Found: C, 53.40; H, 5.35; S, 10.29.

Step B: (3-Chloro-4-Aminophenyl)acetic Acid

10 The (3-chloro-4-acetamidophenyl)thioacetomorpholide (93.8 g., 0.3 mole) is added to 6N hydrochloric acid (500 ml.) and the mixture is refluxed for 1½ hours. The mixture then is cooled to 60°C. and filtered. The filtrate is evaporated to dryness under reduced pressure at about 80°C. and the residue is taken up in water (1 l.). The solution is brought to pH 6 by the addition of a 20 percent sodium hydroxide solution and then to pH 8 with a 10 percent sodium bicarbonate solution. The solution is stirred with decolorizing charcoal for 1 hour, warmed to 80°C. and filtered through a pad of diatomaceous earth. The warm solution is acidified with acetic acid and cooled to about 10°C. The pale yellow solid that separates is collected and is crystallized from water to obtain 43.6 g. (78 percent yield) of (3-chloro-4-aminophenyl)acetic acid, m.p. 136°-137°C.

Elemental analysis for $C_8H_8CLNO_2$:

Calc.: C, 51.76; H, 4.34; N, 7.55;

Found: C, 52.14; H, 4.25; N, 7.74.

Step C: (3-Chloro-4-Cyanophenyl)acetic Acid

Concentrated hydrochloric acid (50 ml.) is added dropwise over a period of 15 minutes to a solution of sodium nitrite (21 g.) in water (100 ml.) at 0°C. with stirring. A solution of (3-chloro-4-aminophenyl)acetic acid (37.0 g., 0.2 mole) in a mixture of concentrated hydrochloric acid (20 ml.) and water (200 ml.) is cooled to 10°C. and is added slowly, with stirring, to the solution of nitrous acid prepared above maintaining the temperature of the reaction mixture at 0°-5°C. by external cooling. Concurrently, additional solid sodium nitrite (10 g.) (total 31 g., 0.45 mole) is added in small portions to the reaction mixture. The mixture then is stirred at 0°-5°C. for 20 minutes and the excess nitrous acid is destroyed by the addition of a solution of urea (15 g., 0.25 mole) in water (50 ml.). Caution: The remainder of this preparation must be run in a good hood as hydrogen cyanide gas is evolved. The cold dark red-black diazonium solution then is added portionwise to a well-stirred cold (10°C.) solution of cuprous cyanide (20 g., 0.22 mole), potassium cyanide (46 g., 0.70 mole) and sodium acetate trihydrate (400 g., 3.0 mole) in water (650 ml.). The black mixture is stirred at 25°C. for 1 hour, at 50°C. for 1 hour and then kept at 20°-25°C. for 16-20 hours. The mixture then is heated to 60°C. and filtered by gravity to remove some tarry material. the filtrate is acidified to Congo Red with concentrated hydrochloric acid. A tan solid, which precipitates, is removed by suction filtration and discarded. The filtrate is cooled and extracted several times with ether. The combined ether extracts are washed with a saturated sodium chloride solution, dried over sodium sulfate, filtered and the ether evaporated under reduced pressure. The yellow brown residual oil solidifies slowly to a dark solid (30 g., m.p. 103°-112°C.). The crude product is dissolved in ether (800 ml.), treated with decolorizing charcoal and the solution evaporated to 150 ml. Ligroin (about 150 ml.)

is added in small portions to incipient precipitation and the mixture is cooled to 0°C. for 16 hours. This type of recrystallization is repeated to obtain 15.2 g. (39 percent yield) of (3-chloro-4-cyanophenyl)acetic acid, m.p. 113°-115°C.

Elemental analysis for $C_9H_6ClNO_2$:

Calc.: C, 55.26; H, 3.09; N, 7.16; Cl, 18.13;
Found: C, 55.36; H, 2.98; N, 7.21; Cl, 18.14.

Step D: (3-Chloro-4-Formylphenyl)acetic Acid

(3-Chloro-4-cyanophenyl)acetic acid (15.6 g., 0.08 mole) is dissolved in 65 percent aqueous formic acid (150 ml.) and Raney nickel alloy (20 g.) is added. The mixture is stirred and refluxed for 1½ hours. The reaction mixture is then cooled to 60°C. and additional Raney alloy (28 g.) is added slowly (foaming). The reaction mixture is again stirred and refluxed for 1½ hours. The reaction mixture is cooled, filtered through diatomaceous earth (suction) and the residue is washed on the filter with hot water (300 ml.). The aqueous filtrate is reserved and the residue in the filter funnel is then extracted with hot ethanol (400 ml.) for 10 minutes. The extract is filtered as above and the residue washed with 300 ml. of hot alcohol. The combined alcoholic extracts are filtered and concentrated to 50 ml. under reduced pressure. The concentrated alcoholic solution is then added to the original aqueous filtrate and the whole is concentrated at reduced pressure to 100-150 ml. The residue is diluted with water (1 l.) and the aqueous mixture is extracted with chloroform (4 × 200 ml.). The chloroform extract is washed with a saturated sodium chloride solution and dried over sodium sulfate. The chloroform is removed by evaporation to afford a pale yellow residue which is recrystallized from benzene (charcoal) to yield 8.1 g. of (3-chloro-4-formylphenyl)acetic acid, m.p. 107°-109°C. This product is satisfactory for the next step. A sample may be further crystallized from ether-cyclohexane (7:5) to obtain substantially pure (3-chloro-4-formylphenyl)acetic acid, m.p. 110°-112°C.

Elemental analysis for $C_9H_7ClO_3$:

Calc.: C, 54.43; H, 3.55; Cl, 17.85;
Found: C, 54.51; H, 3.63; Cl, 17.75.

Step E: [3-Chloro-4-(2-Nitro-1-propenyl)phenyl]acetic Acid

A mixture of (3-chloro-4-formylphenyl)acetic acid (1.0 g., 0.005 mole), n-butylamine (0.8 g., 0.011 mole) and benzene (15 ml.) is heated at reflux under a constant water separator for 1½ hours (A small quantity of water is thus removed from the reaction mixture). The yellow solution is concentrated to dryness under vacuum to afford [4-(N-n-butylformimidoyl)-3-chlorophenyl]acetic acid as a gum. The [4-(N-n-butylformimidoyl)-3-chlorophenyl]acetic acid is dissolved in nitroethane (1.4 g., 0.019 mole) and acetic acid (5 ml.) and is heated at reflux for several minutes, the solution is poured into water and ice and the mixture is acidified with concentrated hydrochloric acid and cooled. The crude product is collected and is recrystallized from benzene-cyclohexane to afford 0.3 g. (23 percent yield) of [3-chloro-4-(2-nitro-1-propenyl)phenyl]acetic acid, m.p. 131°-135°C.

Elemental analysis for $C_{11}H_{10}ClNO_4$:

Calc.: C, 51.68; H, 3.94; N, 5.50;
Found: C, 51.96; H, 3.82; N, 5.34.

EXAMPLE 3

[4-(2-Nitro-1-Propenyl)-2-Methylphenyl]acetic Acid
Step A: (4-Acetamido-2-Methylphenyl)acetothiomorphilide

4-Acetyl-3-methylacetanilide (64.5 g., 0.337 mole) and flowers of sulfur (11.9 g., 0.372 mole) is mixed in a 300 ml. flask. Morpholine (32.4 g., 0.372 mole) is added and the flask is placed in an oil-bath at 100°C.

5 An air condenser is added and the bath temperature brought to 130°C. and held at 125°-130°C. for 7 hours. The dark brown liquid is then poured with vigorous stirring into warm water (1 l.). The product oils out at first but then solidifies into a tan powder after a few minutes. The crude product is crystallized from ethanol to afford 51.0 g. of (4-acetamido-2-methylphenyl)acetothiomorphilide, m.p. 174°-176°C.

Elemental analysis for $C_{15}H_{20}N_2O_2S$:

Calc.: C, 61.61; H, 6.89; N, 9.58;
15 Found: C, 61.31; H, 6.83; N, 9.49.

Step B: (4-Amino-2-Methylphenyl)acetic Acid

A 2 l. round-bottomed flask is charged with (4-acetamido-2-methylphenyl)acetothiomorphilide (87.5 g., 0.3 mole), concentrated hydrochloric acid (250 ml.) and water (500 ml.). The mixture is stirred magnetically on a steam bath. The reaction mixture becomes clear after about ½ hour and the heating and stirring are continued for 3 hours. The clear solution is evaporated under reduced pressure and the residual solid is dissolved in hot water (500 ml.) and is filtered. The clear yellow filtrate is made weakly alkaline (pH of 8) with a 20 percent sodium hydroxide solution (140 ml.) and then is acidified with glacial acetic acid (25 ml.) to a pH of 5 and set aside to crystallize. Filtration yields 39.6 g. of (4-amino-2-methylphenyl)acetic acid, m.p. 187°-190°C. as a beige powder. Several recrystallizations from ethanolwater afford substantially pure product, m.p. 192°-194°C.

Elemental analysis for $C_9H_{11}NO_2$:

Calc.: C, 65.45; H, 6.71; N, 8.48;
Found: C, 66.07; H, 6.76; N, 8.54.

Step C: (4-Cyano-2-Methylphenyl)acetic Acid

A solution of sodium nitrite (20.8 g., 0.30 mole) in water (80 ml.) is added dropwise to a well stirred suspension of (4-amino-2-methylphenyl)acetic acid (33.0 g., 0.20 mole) in water (200 ml.) and concentrated hydrochloric acid (80 ml.) at 0°C. After the addition, the clear diazonium solution is stirred at 0°C. for 1 hour and then the excess nitrous acid is destroyed by the dropwise addition of urea (10 g.) in water (25 ml.). The clear tan solution (turned dark red on standing) is added portionwise to a well stirred solution of cuprous cyanide (20.0 g., 0.204 mole), potassium cyanide (46.0 g., 0.732 mole), and sodium acetate trihydrate (334 g., 2.46 mole) in water (500 ml.) at 0°C. The deep purple solution is stirred at room temperature for one hour, at 50°C. for 1 hour, and then overnight at room temperature. The reaction mixture is filtered and the filtrate is acidified with concentrated hydrochloric acid (250 ml.). After cooling to about 5°C. the (4-cyano-2-methylphenyl)acetic acid is obtained as a tan powder, 30.75 g., m.p. 160°-170°C. Recrystallization from an ethanol-water mixture yields 16.4 g. of (4-cyano-2-methylphenyl)acetic acid, m.p. 175°-176.5°C. Another recrystallization from ethanol-water mixture affords the analytical sample with a m.p. of 176.5°-177°C.

Elemental analysis for $C_{10}H_9NO_2$:

Calc.: C, 68.56; H, 5.18; N, 8.00;
65 Found: C, 68.68; H, 5.20; N, 8.06.

Step D: (4-Formyl-2-Methylphenyl)acetic Acid

Raney nickel alloy (30 g.), (4-cyano-2-methylphenyl)-acetic acid (29.2 g., 0.165 mole), and 75 percent aqueous formic acid (450 ml.) are refluxed

with vigorous stirring for one hour. The mixture is cooled, filtered by suction, and the residue is washed with warm ethanol (3×100 ml.). The filtrate and washings are combined and evaporated under reduced pressure to about 300 ml. The concentrate is cooled, diluted with water (1 l.) and is extracted with several portions of chloroform (4×200 ml.). The chloroform extracts are combined, dried over magnesium sulfate and evaporated under reduced pressure. The crude product is crystallized from water to afford 16.3 g. of (4-formyl-2-methylphenyl)-acetic acid, m.p. 117°–118.5°C.

Elemental analysis for $C_{10}H_{10}O_3$:

Calc.: C, 67.40; H, 5.66;

Found: C, 67.47; H, 5.80.

Step E: [4-(2-Nitro-1-Propenyl)-2-Methylphenyl]acetic Acid

(4-Formyl-2-methylphenyl)acetic acid (7.1 g., 0.04 mole), n-butylamine (8.0 ml., 0.08 mole), and benzene (150 ml.) are refluxed under a water separator for 2 hours. The benzene is evaporated under reduced pressure to afford 4-(N-n-butylformimidoyl)phenylacetic acid as a pale yellow powder. The 4-(N-n-butylformimidoyl)phenylacetic acid is dissolved in a solution of nitroethane (36 ml., 0.50 mole) and acetic acid (50 ml.) and is heated at reflux for several minutes. The resulting green solution is cooled and poured into cold water (600 ml.) and stirred vigorously at room temperature for 5 hours. After cooling overnight, in a refrigerator, the product is collected as a light green powder, 8.0 g., m.p. 153°–156°C. Recrystallization from acetic acid-water yields 6.5 g. of substantially pure [4-(2-nitro-1-propenyl)-2-methylphenyl]acetic acid as pale green thin plates, m.p. 157°–158°C.

Elemental analysis for $C_{12}H_{13}NO_4$:

Calc.: C, 61.27; H, 5.57; N, 5.96;

Found: C, 60.85; H, 5.51; N, 6.27.

EXAMPLE 4

4-(2-Nitro-1-Propenyl)cinnamic Acid

4-Formylcinnamic acid (3.5 g., 0.02 mole), n-butylamine (4 ml., 0.040 mole), and benzene (100 ml.) are refluxed under a water separator for one hour. The benzene is evaporated under reduced pressure to afford 4-(N-n-butylformimidoyl)-cinnamic acid as an oil which is heated to gentle reflux with nitroethane (8 ml., 0.111 mole) and acetic acid (20 ml.). The resulting tan solution is allowed to cool to room temperature to afford the crude product 3.2 g., m.p. 232°–234°C. as small yellow needles. Recrystallization from acetic acid affords 2.95 g. of substantially pure 4-(2-nitro-1-propenyl)-cinnamic acid, m.p. 232°–232.5°C.

Elemental analysis for $C_{12}H_{11}NO_4$:

Calc.: C, 61.80; H, 4.75; N, 6.01;

Found: C, 62.11; H, 4.55; N, 6.13.

EXAMPLE 5

[3-(2-Nitro-1-Propenyl)phenyl]acetic Acid

Step A: (3-Formylphenyl)acetic Acid

A mixture of 3-cyanophenylacetic acid (10.5 g., 0.065 mole), Raney Alloy (11.0 g.), and 65 percent aqueous formic acid (200 ml.) are heated at reflux for 45 minutes with stirring. After cooling, an additional 10 g. of Taney Alloy is added and the reaction mixture is again heated at reflux for 1 hour. The reaction mixture is filtered and the insoluble residue is triturated with warm ethanol and filtered again.

The filtrates are concentrated to near dryness under vacuum and the residue taken up in water; the aqueous mixtures are combined and extracted with several portions of chloroform. After drying over sodium sulfate, the chloroform solution is concentrated to dryness under vacuum to afford 3-formylphenylacetic acid, a pale yellow solid. The product is recrystallized from benzene to afford 6.5 g. (61% yield) of (3-formylphenyl)acetic acid, m.p. 97°–99°C.

Elemental analysis for $C_9H_8O_3$:

Calc.: C, 65.85; H, 4.91;

Found: C, 65.43; H, 4.78.

Step B: [3-(2-Nitro-1-Propenyl)phenyl]acetic Acid
A mixture of 3-formylphenylacetic acid (1.64 g.,

15 0.01 mole), n-butylamine (1.55 g., 0.021 mole) and benzene (25 ml.) is heated at reflux under a constant water separator for 1½ hours; a small quantity of water (0.1 ml.) is thus removed from the reaction mixture. The yellow solution is concentrated to dryness under 20 vacuum to afford [3-(N-n-butylformimidoyl)phenyl]acetic acid as an oily residue which is taken up in nitroethane (2.7 g., 0.036 mole), acetic acid (10 ml) and heated to reflux for several minutes. The solution is poured into water and ice and the reaction mixture is 25 acidified with concentrated hydrochloric acid and cooled. The crude product is collected and recrystallized from benzene-cyclohexane to afford 1.05 g. (48 percent yield) of [3-(2-nitro-1-propenyl)phenyl]-acetic acid, m.p. 70°–72°C.

Elemental analysis for $C_{11}H_{11}NO_4$:

Calc.: C, 59.72; H, 5.02; N, 6.33;

Found: C, 59.66; H, 4.49; N, 6.38.

EXAMPLE 6

35 [4-(2-Nitro-1-propenyl)-1-Naphthyl]acetic Acid

Step A: Ethyl (4-Bromo-1-Naphthyl)acetate

(4-Bromo-1-naphthyl)acetic acid (101 g., 0.382 mole) is dissolved by warming and stirring in thionyl chloride (1.0 l.) and the resulting yellow solution is refluxed for 40 2 hours. The excess thionyl chloride is removed under reduced pressure. The residual brown liquid is washed twice with anhydrous benzene (2×200 ml.) and evaporated to dryness each time to remove the last traces of thionyl chloride. To the residual brown oil is added 45 absolute ethanol (1.0 l.) containing pyridine (31.7 g., 0.40 mole). After the initial exothermic reaction, the solution is heated under reflux for 45 minutes and the ethanol is evaporated at reduced pressure. The light brown solid is dissolved in ether (500 ml), washed successively with water, two portions of saturated sodium bicarbonate [to remove any 4-formyl-1-naphthyl]acetic acid formed] and water. The ether solution is dried over magnesium sulfate, filtered and the ether is evaporated. The residual oil solidifies into a tan crystalline mass of needles, 108 g., m.p. 43°–45.5°C. The crude product is distilled under vacuum to yield ethyl (4-bromo-1-naphthyl)acetate as a light yellow liquid, 50 103.5 g., b.p. 130°–135°C./0.05–0.07 mm. which crystallizes immediately upon cooling, m.p. 44°–46°C.

Elemental analysis for $C_{14}H_{13}BrO_2$:

Calc.: C, 57.36; H, 4.47;

Found: C, 57.13; H, 4.38.

Step B: Ethyl (4-Cyano-1-Naphthyl)acetate

In a 1 l. flask fitted with a condenser and a stirrer is placed ethyl (4-bromo-1-naphthyl)acetate (103 g., 0.352 mole), cuprous cyanide (35 g., 0.375 mole), dimethylformamide (600 ml.), and pyridine (5 ml.). The

mixture is heated under reflux with vigorous stirring for 6 hours. This hot solution is poured, with stirring, into an ammonium hydroxide solution (2 l., 15N) containing crushed ice (1.5 dg.). The resulting blue liquid and red-brown solid is extracted with chloroform (8 $\times$ 500 ml.), the extract is washed with dilute hydrochloric acid, water, and dried over magnesium sulfate. The chloroform is evaporated under reduced pressure and the dark residual oil is distilled under vacuum to afford ethyl (4-cyano-1-naphthyl)-acetate as a reddish-orange oil, 75.4 g., b.p. 165°–173°C./0.03–0.05 mm. which solidifies upon standing, m.p. 55°–59°C. This solid is recrystallized from cyclohexane-chloroform to afford 61 g. of ethyl (4-cyano-1-naphthyl)acetate, m.p. 61.5°–63.0°C. An analytical sample is prepared by recrystallization from cyclohexane-petroleum ether to obtain a pure sample, m.p. 63.5°–64.5°C.

Elemental analysis for $C_{15}H_{13}NO_2$:

Calc.: C, 75.30; H, 5.48; N, 5.85;
Found: C, 75.51; H, 5.42; N, 5.80.

Step C: ethyl (4-Formyl-1-naphthyl)acetate

Raney nickel alloy (61 g.), ethyl (4-cyano-1-naphthyl)-acetate (61 g., 0.255 mole), and 75 percent aqueous formic acid (1 l.) are refluxed with vigorous stirring for 1½ hours in a 5 l. flask. The reaction mixture is then cooled slightly and an additional charge of alloy (122 g.) is added with water (350 ml.). The heating and stirring are continued for an additional 2 hours. Much foaming occurs but because of the size of the flask offers no problem. The reaction mixture then is cooled, filtered, and the flask and residue are washed with several portions of warm ethanol (2 $\times$ 400 ml.). The washings and the original filtrate are combined and evaporated under reduced pressure to about 1 l. The greenish brown solution is poured into 4 l. water and extracted with chloroform (8 $\times$ 250 ml.). The beige extracts are combined and washed with a saturated sodium bicarbonate solution (2 $\times$ 500 ml.) and then dried over magnesium sulfate. The chloroform is evaporated under reduced pressure to yield the crude ethyl (4-formyl-1-naphthyl)acetate, 34.7 g., as a brown oil. Distillation affords substantially pure ethyl (4-formyl-1-naphthyl)acetate as a faint yellow oil, 27.7 g., b.p. 157°–164°C./0.09–0.10 mm.

Elemental analysis for $C_{15}H_{14}O_3$:

Calc.: C, 74.36; H, 5.83;
Found: C, 73.52; H, 5.81.

Step D: [4-(2-Nitro-1-Propenyl)-1-Naphthyl]acetic Acid

Ethyl (4-formyl-1-naphthyl)acetate (5.24 g., 0.0218 mole), n-butylamine (2.16 ml., 0.0218 mole), and benzene (80 ml.) are refluxed under a water separator for 2½ hours. The benzene is evaporated under reduced pressure to afford ethyl [4-(N-n-butylformimidoyl)-1-naphthyl]acetate as a yellow oil. The ethyl [4-(N-n-butylformimidoyl)-1-naphthyl]acetate is dissolved in a solution of acetic acid (40 ml) and nitroethane (14.5 ml., 0.201 mole). The resulting yellow solution is heated to gentle reflux and then the solution is evaporated under reduced pressure. The oily orange residue is dissolved in acetic acid (100 ml.). Water (40 ml.) containing concentrated hydrochloric acid (4 ml.) is then added and the solution is refluxed for 1½ hours. The resulting light brown solution is poured, with stirring, into cold water (500 ml.) and the product sepa-

rates as a light yellow powder, 4.25 g., m.p. 160°–180°C. This crude product is recrystallized seven times from ethanol water to yield 0.56 g. of substantially pure [4-(2-nitro-1-propenyl)-1-naphthyl]acetic acid as tiny yellow needles, m.p. 191°–193°C.

Elemental analysis for $C_{15}H_{13}NO_4$:

Calc.: C, 66.41; H, 4.83;
Found: C, 66.05; H, 5.16.

EXAMPLE 7

[4-(2-Nitro-1-Propenyl)-1-Naphthyl]acetic Acid

Step A: (4-Formyl-1-Naphthyl)acetic Acid

The sodium bicarbonate extracts from Example 6, Step A, are combined and acidified with dilute hydrochloric acid to afford 10.7 g. of crude 4-formyl-1-naphthylacetic acid as a light beige powder, m.p. 180°–184°C. Several recrystallizations from an ethanol-water mixture yield substantially pure (4-formyl-1-naphthyl)acetic acid, m.p. 192.5°–193.5°C.

Elemental analysis for $C_{13}H_{10}O_3$:

Calc.: C, 72.89; H, 4.71;
Found: C, 73.08; H, 4.66.

Step B: [4-(2-Nitro-1-Propenyl)-1-Naphthyl]acetic Acid

(4-Formyl-1-naphthyl)acetic acid (2.14 g., 0.01 mole), n-butylamine (2.0 ml., 0.02 mole), and benzene (50 ml.) are refluxed under a water separator for 3 hours. The benzene is evaporated under reduced pressure to afford [4-(N-n-butylformimidoyl)-1-naphthyl]acetic acid as an orange oil. The [4-(N-n-butylformimidoyl)-1-naphthyl]acetic acid is dissolved in a solution of nitroethane (9 ml., 0.125 mole) and acetic acid (25 ml.) and heated to reflux for several minutes. The resultant clear orange liquid is cooled and poured, with stirring, into cold water (300 ml.). The product separates as a gum which solidifies on standing at 5°C. overnight. This crude product (2.4 g.) is recrystallized 10 times from an ethanol water mixture to yield 0.17 g. of substantially pure [4-(2-nitro-1-propenyl)-1-naphthyl]acetic acid as a yellow powder, m.p. 192°–193.5°C.

Elemental analysis for $C_{15}H_{13}NO_4$:

Calc.: C, 66.41; H, 4.83;
Found: C, 66.13; H, 4.91.

EXAMPLE 8

{3-[2,3-Dichloro-4-(2-Nitro-1-Propenyl)phenyl]} propionic Acid

Step A: α,α' -2,3-Tetrachloro-p-Xylene

To 2,3-dichloro-p-xylene (175 g., 1 mole) is added, gradually, phosphorous pentachloride (408 g., 2 mole) with stirring. With continued stirring, the mixture is heated to 190°–200°C. until hydrogen chloride gas ceases to be evolved. The mixture then is allowed to cool. The mixture is added carefully to water and the organic material is taken up in chloroform. The chloroform extract is washed with water,

10 percent sodium bicarbonate and with water, dried over sodium sulfate and the chloroform is evaporated to afford α,α' -2,3-tetrachloro-p-xylene which is used directly in the next step.

Step B: 2,3-Dichloroterephthalic Aldehyde

Hexamine (62 g., 0.44 mole) is dissolved in warm chloroform (500 ml.) with stirring. Then α,α' -2,3-tetrachloro-p-xylene (48.8 g., 0.2 mole) in a minimum amount of warm chloroform is added. the mixture is re-

fluxed for 4 hours and then allowed to cool. The hexaminium salt that separates is collected and washed with chloroform. The hexaminium salt (52.4 g., 0.1 mole) is added to 50 percent acetic acid (180 ml.) and the mixture is refluxed for about 2 hours. The mixture is acidified to Congo Red and refluxed for an additional 5 minutes. The mixture is cooled and diluted with water until the separation of the 2,3-dichloroterephthalic aldehyde is complete. The 2,3-dichloroterephthalic aldehyde is collected and purified by crystallization from a suitable solvent such as alcohol or alcohol-water.

Step C: 2,3-dichloro-4-Formylcinnamic Acid

A mixture of 20.3 g. (0.1 mole) of 2,3-dichloroterephthalic aldehyde, acetic anhydride (10.2 g., 0.1 mole) and anhydrous sodium acetate (10 g.) are combined and heated at 180°C. under a short air condenser for 8 hours. The cooled mixture is diluted with water and extracted with ether. The ether solution is extracted thoroughly with dilute sodium bicarbonate solution. The aqueous extract is washed with ether and acidified with dilute hydrochloric acid. The 2,3-dichloro-4-formylcinnamic acid that separates is collected, dried and recrystallized from benzene or alcohol.

Step D: 3-(2,3-Dichloro-4-Formylphenyl)Propionic Acid

2,3-Dichloro-4-formylcinnamic acid (10 g.) is dissolved in ethanol and 250 mg. of rhodium on carbon catalyst (5 percent) is added. The mixture is hydrogenated at 30 p.s.i. original pressure. The hydrogenation is interrupted when exactly 1 mole of hydrogen has been absorbed. The catalyst is removed and the alcohol is evaporated. The residue is crystallized from benzene to obtain 3-(2,3-dichloro-4-formylphenyl)propionic acid.

Step E: {3-[2,3-dichloro-4-(2-Nitro-1-Propenyl)phenyl]} Propionic Acid

By substituting for the (3-chloro-4-formylphenyl)acetic acid of Example 2, Step E, an equimolar quantity of 3-(2,3-dichloro-4-formylphenyl)propionic acid and by following substantially the procedure described therein, there is obtained. {3-[2,3-dichloro-4-(2-nitro-1-propenyl)phenyl]} propionic acid.

EXAMPLE 9

3-[2,3-Dichloro-4-(2-nitro-1-Propenyl)Phenyl]-2-Methylacrylic Acid

Step A: 3-(2,3-Dichloro-4-Formylphenyl)-2-Methylacrylic Acid

By substituting for the acetic anhydride and sodium acetate of Example 8, Step C, an equimolar quantity of propionic anhydride and sodium propionate and by following substantially the procedure described therein, there is obtained 3-(2,3-dichloro-4-formylphenyl)-2-methylacrylic acid.

Step B: 3-[2,3-Dichloro-4-(2-nitro-1-Propenyl)Phenyl]-2-Methylacrylic Acid

By substituting for the (3-chloro-4-formylphenyl)acetic acid of Example 2, Step E, an equimolar quantity of 3-(2,3-dichloro-4-formylphenyl)-2-methylacrylic acid and by following substantially the procedure described therein, there is obtained 3-[2,3-dichloro-4-(2-nitro-1-propenyl)phenyl]-2-methylacrylic acid.

EXAMPLE 10

[2,3-Dichloro-4-(2-Nitro-1-Propenyl)]Cinnamic Acid

By substituting for the (3-chloro-4-formylphenyl)acetic acid of Example 2, Step E, an equimolar quantity

of 2,3-dichloro-4-formylcinnamic acid and by following substantially the procedure described therein, there is obtained [2,3-dichloro-4-(2-nitro-1-propenyl)]cinnamic acid.

EXAMPLE 11

4-(2-Nitro-1-Propenyl)hydrocinnamic Acid

Step A: 4-Cyanohydrocinnamic Acid

A solution of sodium nitrite (20.8 g., 0.30 mole) in water (80 ml.) is added dropwise to a well-stirred solution of 4-aminohydrocinnamic acid (34.0 g., 0.206 mole) in water (200 ml.) and concentrated hydrochloric acid (80 ml.) at 0°C. After the addition, the clear diazonium solution is stirred at 0°C. for 1 hour and then the excess nitrous acid is destroyed by the dropwise addition of urea (10 g.) in water (25 ml.). The clear tan solution is added portionwise to a well stirred solution of cuprous cyanide (20.0 g., 0.204 mole), potassium cyanide (46.0 g., 0.732 mole), and sodium acetate trihydrate (334 g., 2.46 mole) in water (500 ml.) at 0°C. The dark solution is stirred at room temperature for 1 hour at 50°C. for 1 hour, and then overnight at room temperature. The mixture is then warmed to 60°C. and filtered by gravity. The filtrate is treated with concentrated hydrochloric acid (250 ml.) to yield the crude product as a tan solid. This tan solid is extracted in a Soxhlet with ether. Evaporation of the ether yields 22.2 g. of product, m.p. 135°-139°C. Recrystallization from water yields the substantially pure 4-cyanohydrocinnamic acid as yellow needles, 18.5 g., m.p. 138°-139°C.

Step B: 4-Formylhydrocinnamic Acid

Raney nickel alloy (20 g.), 4-cyanohydrocinnamic acid (18.5 g., 0.106 mole), and 75 percent aqueous formic acid (300 ml.) are refluxed with vigorous stirring for 1 hour. The mixture is cooled, filtered by suction, and the residue washed with three 100 ml. portions of warm ethanol. The filtrate and washings are combined and evaporated under reduced pressure to about 300 ml. The concentrate is cooled, diluted with water (1 l.), and extracted with four 200 ml. portions of chloroform. The extracts are combined, dried over magnesium sulfate and evaporated under reduced pressure to yield the crude product as off white needles, 13.3 g., m.p. 136°-138°C. An analytical sample, m.p. 135.5°-136.5°C, is prepared by recrystallization from benzene.

Elemental analysis for $C_{10}H_{10}O_3$:

Calc.: C, 67.40; H, 5.66;

Found: C, 67.42; H, 5.36.

Step C: 4-(2-Nitro-1-Propenyl)hydrocinnamic Acid

4-Formylhydrocinnamic acid (5.33 g., 0.03 mole), n-butylamine (6 ml., 0.06 mole), and benzene (125 ml.) are refluxed under a water separator for 1½ hours. The benzene is evaporated under reduced pressure to afford 4-(N-n-butylformimidoyl)hydrocinnamic acid as a yellow oil which is heated to gentle reflux with nitroethane (10.8 ml., 0.15 mole) and acetic acid (40 ml.). The resulting dark green solution is cooled and poured with stirring into cold water (400 ml.). The crude product obtained as a light green powder, 6.6 g., m.p. 124°-126°C. Recrystallization from acetic acid and water affords substantially pure 4-(2-nitro-1-propenyl)-hydrocinnamic acid as green needles, 6.1 g., m.p. 126.5°-127.5°C.

Elemental analysis for $C_{12}H_{13}NO_4$:

Calc.: C, 61.27; H, 5.57; N, 5.96;

Found: C, 61.62; H, 5.58; N, 6.14.

EXAMPLE 12

[2,3,5-Trimethyl-4-(2-Nitro-1-Propenyl)phenyl]acetic Acid Step A: 2',3',5'-Trimethyl-4'-Acetamidoacetophenone

To a solution of 2,3,6-trimethylacetanilide (17.7 g., 0.1 mole) and acetyl chloride (23.6 g., 0.3 mole) in dichloromethane (100 ml.) cooled in an ice bath is added slowly aluminum chloride (26.6 g., 0.2 mole). After the addition is complete, the reaction mixture is warmed slowly to reflux for two hours. The solvent is decanted and to the residue is added ice water (100 ml.) and concentrated hydrochloric acid (10 ml.). The product is extracted with chloroform. The chloroform extract is washed with water and dried over anhydrous magnesium sulfate. The solution is filtered and the solvent removed at reduced pressure to yield 2',3',5'-trimethyl-4'-acetamidoacetophenone.

Step B: (2,3,5-Trimethyl-4-Acetamidophenyl)thioacetomorpholide

By substituting for the 3-chloro-4-acetamidoacetophenone of Example 2, Step A, an equivalent amount of 2',3',5'-trimethyl-4'-acetamidoacetophenone and following substantially the procedure described therein, there is obtained (2,3',5-Trimethyl-4-acetamidophenyl)thioacetomorpholide.

Step C: (2,3,5-Trimethyl-4-Aminophenyl)acetic Acid

By substituting for the (3-chloro-4-acetamidophenyl)-thioacetomorpholide of Example 2, Step B, an equivalent amount of (2,3,5-Trimethyl-4-acetamidophenyl)thioacetomorpholide and following substantially the procedure described therein, there is obtained (2,3,5-Trimethyl-4-aminophenyl)acetic acid.

Step D: (2,3,5-Trimethyl-4-Cyanophenyl)acetic acid

By substituting for the (3-chloro-4-aminophenyl)acetic acid of Example 2, Step C, an equimolar quantity of (2,3,5-Trimethyl-4-aminophenyl)acetic acid and following substantially the procedure described therein, there is obtained (2,3,5-Trimethyl-4-cyanophenyl)acetic acid.

Step E: (2,3,5-Trimethyl-4-Formylphenyl)acetic Acid

By substituting for the (3-chloro-4-cyanophenyl)acetic acid of Example 2, Step D, an equimolar quantity of (2,3,5-Trimethyl-4-cyanophenyl)acetic acid and following substantially the procedure described therein, there is obtained (2,3,5-Trimethyl-4-formylphenyl)acetic acid.

Step F: [2,3,5-Trimethyl-4-(2-Nitro-1-Propenyl)phenyl]acetic acid

By substituting for the (3-chloro-4-formylphenyl)acetic acid of Example 2, Step E, an equimolar quantity of (2,3,5-Trimethyl-4-formylphenyl)acetic acid and following substantially the procedure described therein, there is obtained [2,3,5-Trimethyl-4-(2-nitro-1-propenyl)phenyl]acetic acid.

EXAMPLE 13

[2,3,5,6-Tetramethyl-4-(2-Nitro-1-Propenyl)phenyl]acetic Acid

Step A: 2',3',5',6'-Tetramethyl-4'-Acetamidoacetophenone

To a solution of 2,3,5,6-Tetramethylacetanilide (19.13 g., 0.1 mole) and acetyl chloride (23.6 g., 0.3 mole) in dichloromethane (100 ml.) cooled in an ice bath is added slowly aluminum chloride (26.6 g., 0.2 mole). After the addition is complete, the reaction mixture is warmed slowly to reflux for 2 hours. The solvent

is decanted and to the residue is added ice water (100 ml.) and concentrated hydrochloric acid (10 ml.). The reaction mixture is worked up substantially as in Example 12, Step A, to obtain 2',3',5',6'-tetramethyl-4'-acetamidoacetophenone.

Step B: (2,3,5,6-Tetramethyl-4-Acetamidophenyl)thioacetomorpholide

By substituting for the 3-chloro-4-acetamidoacetophenone of Example 2, Step A, an equivalent amount of 2',3',5',6'-tetramethyl-4'-acetamidoacetophenone and following substantially the procedure described therein, there is obtained (2,3',5,6-tetramethyl-4-acetamidophenyl)thioacetomorpholide.

Step C: (2,3,5,6-Tetramethyl-4-Aminophenyl)acetic Acid

By substituting for the (3-chloro-4-acetamidophenyl)-thioacetomorpholide of Example 2, Step B, and equivalent amount of (2,3,5,6-tetramethyl-4-acetamidophenyl)thioacetomorpholide and following substantially the procedure described therein, there is obtained (2,3,5,6-tetramethyl-4-aminophenyl)acetic acid.

Step D: (2,3,5,6-Tetramethyl-4-Cyanophenyl)acetic Acid

By substituting for the (3-chloro-4-aminophenyl)acetic acid of Example 2, Step C, an equimolar quantity of (2,3,5,6-tetramethyl-4-aminophenyl)acetic acid and following substantially the procedure described therein, there is obtained (2,3,5,6-tetramethyl-4-cyanophenyl)acetic acid.

Step E: (2,3,5,6-Tetramethyl-4-Formylphenyl)acetic Acid

By substituting for the (3-chloro-4-cyanophenyl)acetic acid of Example 2, Step D, an equimolar quantity of (2,3,5,6-tetramethyl-4-cyanophenyl)acetic acid and following substantially the procedure described therein, there is obtained (2,3,5,6-tetramethyl-4-formylphenyl)acetic acid.

Step F: [2,3,5,6-Tetramethyl-4-(2-Nitro-1-Propenyl)phenyl]acetic Acid

By substituting for the (3-chloro-4-formylphenyl)acetic acid of Example 2, Step E, an equimolar quantity of (2,3,5,6-tetramethyl-4-formylphenyl)acetic acid and following substantially the procedure described therein, there is obtained [2,3,5,6-tetramethyl-4-(2-nitro-1-propenyl)phenyl]acetic acid.

By following the procedure as described in Example 2, Steps A-E, all of the products described in the following table may be prepared. Thus, by substituting the appropriately substituted acetamidoacetophenone for the 3-chloro-4-acetamidoacetophenone of Example 2, Step A, and by following the procedure of Example 2, Steps A-D, there is produced the corresponding substituted formylphenylacetic acid. Then by substituting the formylphenylacetic acid and an appropriate amine for the n-butylamine, there is produced the corresponding [(N-substituted formimidoyl)phenyl]acetic acid. Then by substituting the [(N-substituted formimidoyl)phenyl]-acetic acid and an appropriate nitroalkane or substituted nitroalkane for the [4-(N-n-butylformimidoyl)-3-chlorophenyl]-acetic acid and nitroethane of Example 2, Step E, and by following substantially the procedure described therein, all the products described in Table I may be prepared. The following equation illustrates the reactions of Example 2, Steps A-E, and, together with Table I, illustrate the starting materials, intermediates and [(2-nitro-1-alkenyl)-phenyl]acetic acid products obtained:

The novel compounds of this invention are diuretic and saluretic agents which can be administered in a wide variety of therapeutic dosages in conventional vehicles as, for example, by oral administration in the form of a tablet or by intravenous injection. Also, the daily dosage of the products may be varied over a wide range varying from 5 to 500 mg. The product is preferably administered in subdivided doses in the form of scored tablets containing 5, 10, 25, 50, 100, 150, 250 and 500 milligrams of the active ingredient for the symptomatic adjustment of the dosage to the patient to be treated. These dosages are well below the toxic or lethal dose of the products.

A suitable unit dosage form of the products of this invention can be administered by mixing 50 milligrams of a [(2-nitro-1-alkenyl)aryl]alkanoic (and alkenoic)acid (I) or a suitable salt, ester or amide derivative thereof, with 149 mg. of lactose and 1 mg. of magnesium stearate and placing the 200 mg. mixture into a No. 1 gelatin capsule. Similarly, by employing more of the active ingredient and less lactose, other dosage forms can be put up in No. 1 gelatin capsules and, should it be necessary to mix more than 200 mg. of ingredients together, larger capsules may be employed. Compressed tablets, pills, or other desired unit dosages can be prepared to incorporate the compounds of this invention by conventional methods and, if desired, can be made up as elixirs or as injectable solutions by methods well known to pharmacists.

It is also within the scope of this invention to combine two or more of the compounds of this invention in a unit dosage form or to combine one or more of the compounds of this invention with other known diuretics and saluretics or with other desired therapeutic and/or nutritive agents in dosage unit form.

The following example is included to illustrate the preparation of a representative dosage form:

EXAMPLE 28

Dry-filled capsules containing 50 mg. of active ingredient per capsule

	Per Capsule
[3-Chloro-4-(2-Nitro-1-Propenyl)phenyl]acetic Acid	50 mg.
Lactose	149 mg.
Magnesium Stearate	1 mg.
Capsule (Size No. 1)	200 mg.

The [3-chloro-4-(2-nitro-1-propenyl)phenyl]acetic acid is reduced to a No. 60 powder and then lactose and magnesium stearate are passed through a No. 60 bolting cloth onto the powder and the combined ingredients admixed for 10 minutes and then filled into a No. 1 dry gelatin capsule.

Similar dry-filled capsules can be prepared by replacing the active ingredient of the above example by any of the other novel compounds of this invention.

It will be apparent from the foregoing description that the [(2-nitro-1-alkenyl)aryl]alkanoic (and alkenoic)acid products (I) of this invention constitute a valuable class of compounds which have not been prepared heretofore. One skilled in the art will also appreciate that the processes disclosed in the above examples are merely illustrative and are capable of a wide variation and modification without departing from the spirit of this invention.

What is claimed is:

1. A compound of the formula:

60 wherein R is lower alkyl, lower alkoxy lower alkyl, halo lower alkyl, trihalo lower alkyl, hydroxy lower alkyl, cyano, benzyl or lower cycloalkyl; X is hydrogen, halo or lower alkyl or, taken together, two X radicals on the 5 and 6 carbon atoms of the benzene ring may be joined to form the 1,3-butadienylene linkage; Y is methylene, ethylene, vinylene or methyl substituted vinylene and n is an integer having a value of 1-4, or a

25

non-toxic, pharmaceutically acceptable salt or a lower alkyl ester thereof.

2. A compound of the formula:

wherein R¹ is lower alkyl and X¹ and X² are hydrogen, lower alkyl or halo or X¹ and X², taken together, may

26

be joined to form a 1,3-butadienylene linkage or a non-toxic, pharmaceutically acceptable salt thereof.

3. A compound according to claim 2 wherein R¹ is methyl, X¹ is chloro and X² is hydrogen.

5. 4. A compound according to claim 2 wherein R¹ is methyl and X¹ and X² are joined together to form a 1,3-butadienylene linkage.

5. A compound according to claim 2 wherein R¹ is methyl and X¹ and X² and hydrogen.
